(57) **CLAIM**

The ornamental design for a tubular frame jack, as shown and described.

DESCRIPTION

The present document contains material related to the material of copending, cofiled, U.S. Design patent applications Ser. No. 29/276,337, entitled Low Profile Tubular Frame Jack and U.S. Utility patent application Ser. No. 11/625,980, entitled: Tubular Frame Lifting Apparatus, the disclosures of which are hereby incorporated herein by reference.

FIG. 1 is a rear perspective view of the tubular frame jack, with the lift arm in a retracted position;

FIG. 2 is a left side view of the tubular frame jack, shown in FIG. 1;

FIG. 3 is a right side view of the tubular frame jack, shown in FIG. 1;

FIG. 4 is a top view of the tubular frame jack, shown in FIG. 1;

FIG. 5 is a bottom view of the tubular frame jack, shown in FIG. 1;

FIG. 6 is a front view of the tubular frame jack, shown in FIG. 1;

FIG. 7 is a rear view of the tubular frame jack, shown in FIG. 1; and,

FIG. 8 is a rear perspective view of the tubular frame jack, shown in FIG. 1, with the lift arm in an extended position.

In FIGS. 1-8, the details shown in broken lines are for illustrative purposes only and form no part of the claimed design.
